DANIEL M. DONEHOO, OF BEAVER, PENNSYLVANIA.

Letters Patent No. 61,522, dated January 29, 1867.

IMPROVED SAFETY BRIDLE.

The Schedule referred to in these Letters Patent and making part of the same.

TO ALL WHOM IT MAY CONCERN:

Be it known that I, DANIEL M. DONEHOO, of Beaver, Beaver county, State of Pennsylvania, have invented a new and useful Improved Safety Bridle; and I do hereby declare the following to be a full, clear, and exact description of the nature, construction, and operation of the same, sufficient to enable one skilled in the art to which it appertains to construct and use the same, reference being had to the accompanying drawing, which is made part of this specification, and in which the bridle is shown in position upon a horse:

The ring of the bit is suspended on each side from a ring on the cheek-strap, by a running strap, which, connected primarily to the bit-ring, passes up and through the cheek-ring, is then carried down through the bit-ring and connected to a safety rein; the latter is also connected to the gag rein so that pulling upon the safety rein shortens up the gag rein, and at the same time draws up the bit towards the ring on the cheek-strap.

In the drawings, the head-stall is composed of the cheek-straps A, brow-band B, and throat-latch C; to the ends of the cheek-straps are rings, D, from which the bit E is suspended by rings F in a manner to be described. The strap G is attached to the bit-ring F, and passing thence is carried through the ring D and then downward through the bit-ring and is attached to the ring H, of the safety rein I, which is associated with the line J. To the ring H is likewise attached the bit-end of the gag or riding rein K, which passes through the bit-ring, up the ring H and through the gag-runner L, and thence to the hook on the gig-saddle. When the rein K is used as a riding rein the gag-runner L is dispensed with. It is my design, when it becomes necessary to use the safety rein in driving, that the power exerted shall have the effect of pulling the bit up into the angle of the horse's mouth and not pull backward on the teeth or jaw; at the same time the slack of the gag rein is taken up, and, being shortened, tends to elevate the horse's head and place him more under command. It will also be perceived that the strap G is carried up over the ring D and down again through the bit-ring F, after which it connects with the ring of the safety rein. When the latter is pulled the effect is to give a greater power upon the bit owing to the duplication of the strap G between the rings F D; the bit only rises at half the speed with which the safety rein is pulled but with double the power, (except a trifling loss by friction, of course.) This power at the expense of speed can be increased by unfastening the end of the strap G from the bit-ring and carrying it through the latter and upward to a connection with the cheek-strap A, so as to make it threefold. The device on the respective sides of the animal is of course uniform. When the device is to be used as a riding bridle the driving line J is detached entirely at its point of connection with the bit-ring F, and the safety rein, (somewhat shortened,) in connection with the rein K, becomes the means of handling the horse. The rein K answers for the ordinary travel and the safety rein for emergencies, as it did before. A martingale, (not shown,) may be applied in connection with the device, either by connecting it to the ring H of the safety rein, or so arranged that the ring of the martingale runs upon the line or rein J. Any kind of bit can be used. It is a great advantage to a horse to have an easy bit to travel against, and I am able to afford it, as the means of safety against emergencies do not depend upon the severity of the bit but upon the direction and amount of power exerted upon the mouth of the animal.

Having described my invention, what I claim therein as new, and desire to secure by Letters Patent, is—

The strap G, connecting the bit-ring F, and safety rein I, through the cheek-strap ring D, in combination with the gag or riding rein K, all arranged to operate substantially as and for the purpose specified.

D. M. DONEHOO.
